UNITED STATES PATENT OFFICE

93,619

DESIGN FOR A FLOOR POLISHING MACHINE

Osmund Holm-Hansen, Stratford, and Noble H. Watts, Bridgeport, Conn., assignors to General Electric Company, a corporation of New York

Application August 28, 1934, Serial No. 53,102

Term of patent 14 years

To all whom it may concern:

Be it known that we, OSMUND HOLM-HANSEN and NOBLE H. WATTS, citizens respectively of Norway and the United States, residing respectively at Stratford and Bridgeport, in the county of Fairfield, State of Connecticut, have invented a new, original, and ornamental Design for Floor Polishing Machines, of which the following is a specification, reference being had to the accompanying drawing, forming part thereof.

The figure is a perspective view of the floor-polishing machine, showing our new design.

We claim:

The ornamental design for a floor-polishing machine, as shown.

OSMUND HOLM-HANSEN.
NOBLE H. WATTS.
